No 935

Peter Auguste's design for
Clock Case Front.

Patented Aug 9 1837

Dec. 935

Pietro Lingueanni, of West Meriden, Conn.
Letters Patent No. 935, Dated Aug. 25, 1857.

The schedule referred to in these Letters Patent, and making part of the same.

To all whom it may concern:

Be it known that I, Pietro Lingueanni, of West Meriden, in the County of New Haven, and State of Connecticut, have invented or produced a new and original design for a clock case front, and I do hereby declare that the following is a full, clear and exact description of the same, reference being had to the annexed drawing, making a part of this specification, said drawing being a front elevation of my design.

The design is composed of a grape vine in bearing and scroll work combined, as will be hereinafter described with reference to the accompanying drawing.

A, is the base of the clock case front. Each end of the base is formed of a scroll B, and the bottom or lower end of the base is formed of two scrolls C, C, and the lower ends of the scrolls B, are connected. The upper edge of the base is formed of two simple or plain scrolls E, E. The scrolls referred to it will be seen give a concavo-convexed contour or outline to the base A.

The upper portion A', of the clock case front has its edge formed of a series of convex scrolls F, which give a convex scalloped form to the contour or outline upper part of the front. G, G, are two scrolls which are placed one at each side of the upper part of the front, the upper ends of said scrolls being surmounted by a basket H, containing grapes and leaves, the basket forming the apex of the front.

At each side of the front a grape vine trunk I, is placed. From these trunks, branches project and entwine themselves with the scrolls, previously described, fruit (a) and leaves (b) being connected with the trunk and branches as plainly shown in the drawing.

In the base A, the pendulum opening J, is made, and the dial opening is made in the upper part of the front.

Des. 935

58.

What I claim as new and desire to secure by letters
Patent, is,

The scrolls, vines, and basket combined and
arranged as shown to form an ornamental design for a clock
case front.

and witness
